(57) **CLAIM**

The ornamental design for a home-brew pump, as shown and described.

DESCRIPTION

FIG. 1 is a perspective view of the home-brew pump.

FIG. 2 is a left side view thereof.

FIG. 3 is a right side view thereof.

FIG. 4 is a front view thereof.

FIG. 5 is a bottom view thereof.

FIG. 6 is a top view thereof.

FIG. 7 is a bottom view thereof.

FIG. 8 is a top view of the home-brew pump showing the rotor housing being opened.

FIG. 9 is a top view of the home-brew pump showing the rotor housing being opened.

FIG. 10 is a front view of the home-brew pump showing the rotor being removed from the rotor housing.

FIG. 11 is a back view of the home-brew pump showing the rotor being removed from the rotor housing.

FIG. 12 is a top view of the home-brew pump showing the rotor housing being opened and the rotor being removed from the rotor housing; and,

FIG. 13 is a bottom view of the home-brew pump showing the rotor housing being opened and the rotor being removed from the rotor housing.

The broken lines are included for the purpose of illustrating portions of the home-brew pump that form no part of the claimed design.
